J. BETHENOD

RADIO TRANSMISSION SYSTEM

Filed Aug. 2, 1921

Inventor
JOSEPH BETHENOD

By his Attorney
Dora J. Adams

UNITED STATES PATENT OFFICE.

JOSEPH BETHENOD, OF PARIS, FRANCE.

RADIO TRANSMISSION SYSTEM.

Application filed August 2, 1921. Serial No. 489,306.

To all whom it may concern:

Be it known that I, JOSEPH BETHENOD, a citizen of the Republic of France, and a resident of Paris, France, have invented certain new and useful Improvements in Radio Transmission Systems, of which the following is a specification, accompanied by drawings.

The object of the present invention is to 10 make improvements in radiotelegraphic stations comprising a plurality of high frequency generators. The purpose of the invention is to effect by very simple operations and at the will of the operator, either the 15 simultaneous operation of these generators at the same frequency so as to apply to the antenna the total power of the generating station, or independently to operate these generators at different frequencies so as to 20 obtain a so-called multiplex transmission.

My invention is illustrated in the single figure of the accompanying drawing.

The principle of the invention consists in the division of the usually net shaped 25 antenna A, extended in one direction, into several sections A₁, A₂, A_n, each of which is supplied with current by a high frequency generator G₁, G₂, G_n, and to provide a device for limiting the currents caused by the elec- 30 tromagnetic or electrostatic induction between any two sections.

In this manner, n independent stations will be provided enabling multiplex transmission to the n degree, each station having 35 a wave length slightly different from that of the others. By means of switching means comprising antenna switches S₁, S₂, S_n, and alternator paralleling switches S_p, S'_p, S'', the operator may at will inter-connect all or 40 a part of the stations, whereby if n=3, triplex, or duplex (one transmission having double the power of the other), or simplex transmission is practicable with the total power of the station.

45 The limiting of the induced currents is preferably accomplished by means of an arrangement comprising a self-inductance such as I₁, I'₁, I₂, I'₂, I_n, I'_n and a capacity C₁, C'₁, C₂, C'₂, C_n, C'_n (connected in parallel) which are included in each of the circuits formed by an antenna section, the generator being connected to ground. If the sending is of the n degree, each circuit (n-1) must be protected by the arrangement (all connected in series). Each of 50 these arrangements or trap circuits should

be tuned to one of the frequencies corresponding to one of the n-1 other transmissions, so as to provide an almost infinite impedance to said frequencies. 60

Obviously, the arrangements (trap circuits) of one and the same section may be combined with each other for reducing the total number of the constituting elements. 65

One of the characteristics of the invention resides in the division into n sections of the antenna, in combination with the use of the infinite impedance or so-called frequency traps. 70

The use of such traps with an undivided antenna would not furnish a practical solution of the problem of multiplex transmission because, in order efficaciously to protect each generator against the currents generated by the others, very expensive self-inductances and capacities must be provided to avoid serious losses, i. e. a reduction of the output. This is proved by theory and practice. It may be easily proved that, in case of multiplex operation, the partial use 75 of the antenna has no disadvantage for a given power for each generator. 80

Having described my invention what I claim is:

1. In a radio transmission system, an aerial divided into two separate sections adapted to radiate different wave lengths, generators therefor, and a connection of substantially infinite impedance in each of said sections to the wave length of the other section for limiting induction effects therebetween. 85

2. In a radio transmission system, an aerial divided into two separate sections adapted to radiate different wave lengths, generators therefor, a connection of substantially infinite impedance, in each of said sections to the wave length of the other section for limiting induction effects therebetween, and means for connecting both of 90 said generators to the same section. 95

3. In a radio transmission system, an aerial divided into n separate sections adapted to radiate different wave lengths, n separate generators, and connections in each of said sections, having infinite impedance to frequencies corresponding to the wave lengths radiated by the other sections. 100

4. In a radio transmission system, an aerial divided into a plurality of separate sections, a plurality of generators, means for connecting some of said generators to 110

a desired one of said sections, and the remainder of said generators to the other sections, said generators connected to different sections being adjusted to generate different frequencies, and said generators connected to the same section being adjusted to generate the same frequencies, and circuits of infinite impedance in each of the radiating sections for limiting self induction from the other sections.

5. In a radio transmission system, an aerial divided into n separate sections, n separate generators each of different wave length, connected to said sections, and $n-1$ infinite impedance circuits in each section for limiting self induction from the $n-1$ other sections of different wave length.

10. In a radio transmission system, an aerial divided into two separate sections

adapted to radiate different wave lengths, 20 a pair of generators therefor, and a trap circuit in each section comprising inductance and capacity connected in parallel and tuned to the frequency of the other section.

15. In a radio transmission system, an 25 antenna divided into a plurality of sections, a plurality of generators and means whereby any desired number of said generators may be utilized to feed any section of said antenna.

20. In a radio transmission system, an antenna divided into a plurality of sections, a plurality of generators and switching means for connecting any desired number of said generators in parallel to any antenna 35 section.

JOSEPH BETHENOD.
